UNITED STATES PATENT OFFICE.

LÁSZLÓ CZAKÓ, OF BUDAPEST, HUNGARY.

MEANS FOR HOLDING FILMS IN SPACED COIL FORMS.

Application filed February 16, 1922, Serial No. 537,120, and in Hungary April 2, 1921.

This invention relates to an improved reel for photographic films, the object of the invention being to provide a device of this character having means for exerting pressure on the film at the edges thereof thereby to effectively prevent the film from becoming distorted or warped during development, and simultaneously to maintain the coils of the film separated one from the other.

With the foregoing and other objects in view, which will appear as the description proceeds, the invention consists in the novel features of construction and combination of parts which will be more fully described hereinafter and particularly pointed out in the claims.

In the drawings accompanying and forming part of this specification,

Fig. 1 is a fragmentary perspective view, on a somewhat exaggerated scale, of two portions of a film and its spacing member, illustrating one of the corrugated edges of the latter;

Fig. 2 is a fragmentary sectional view of a coiled film, showing a modified form of the spacing member;

Fig. 3 is a fragmentary plan view of a coiled film, the coils of which are separated in the same manner as shown in Fig. 1;

Fig. 4 is a fragmentary vertical section of a reel constructed in accordance with the present invention, illustrating a film wound thereon; and

Fig. 5 is a plan view of the structure shown in Fig. 4.

The same characters of reference designate the same parts in the different figures of the drawings.

Referring to the drawings, the reel comprises a central hub formed of two enlarged portions 7 and 7^a, the portion 7^a being provided with a tubular extension 9 on which the other hub portion 7 is mounted for sliding movement toward and from its companion member, as shown in Fig. 4. The extension 9 is exteriorly threaded at its free end for the reception of an enlarged head or knob 10, whereby the entire reel may be conveniently lifted and carried from place to place. In each of the hub members 7 and 7^a are secured a plurality of radially extending spokes 6, the spokes of the respective hub members being secured at their outer ends in separate rims 8, whereby one hub

member with its spokes and rim can be entirely separated from the other.

As shown in the drawings, the usual sensitized film 1 is wound in spiral formation around the composite hub formed by the members 7 and 7^a, and if desired, a spacing strip 3, the edges 4 of which are corrugated so as to retain the coils of the sensitized strip 1 in spaced relation, may be wound therewith, as shown at 2 in Figs. 1 and 3. The corrugations 4 of the spacing strip are located at the extreme edges thereof and contact with the film 1 only outside of the usual perforations 5, so that the entire picture field of the film is left entirely clear to be acted on by the developing and fixing solutions.

The hub members 7, 7^a are of such a length and the rims 8 of such width that when the film is in position in the reel the spokes 6 will engage the edges of the film coils slightly before the upper hub member 7 and rim member 8 abut against their companion members, as clearly shown in Fig. 4, so that upon tightening the knob or head 10 to carry the hub members and rim members into abutting engagement the spokes 6 will exert sufficient pressure on the edges of the film to prevent movement thereof, but insufficient to cause distortion or warping of the film. The spokes 6 are each preferably enclosed in a layer 11 of flexible material, such as rubber, as clearly shown in Fig. 2, whereby not only is injury to the edges of the film avoided, but when the hub members are clamped together the edges of the film will "bite" into the flexible coating of the spokes and cause said coating to bulge into the spaces between the coils of the film and thus prevent shifting thereof, so that, even if the spacing strip 3 is omitted the coils will be retained in spaced relation by means of the bulging of said flexible coating.

I am aware that the provision of intermediate strips for retaining the coils of the film spaced apart to permit free access of the treating solutions is not broadly new. However, with all of the devices with which I am familiar, their use is accompanied by the disadvantage that the film is unsupported at its edges, and consequently is free to move and become distorted, thus inducing the formation of air bubbles on the film so that uniformity of treatment is impossible. In contradistinction, the present invention, by the provision of means for exerting local

pressure on the edges of the film, and at the same time providing means for retaining the coils spaced apart, the film is held against any movement whatsoever, and therefore 5 cannot warp, while at the same time free access of the treating fluids is permitted to the spaces between the coils.

Having thus described my invention, what I claim is:

- 10 1. A device of the class described, comprising, in combination, a hub adapted to receive a strip of film in spiral formation, means for exerting pressure locally on the edges of the film, and means for retaining 15 the coils of said film in spaced relation.
2. A device of the class described, comprising, in combination, a two-part hub adapted to receive a strip of film in spiral formation, one part being movable toward and away 20 from the other, means carried by said hub for locally engaging the edges of the film, means for clamping said hub parts together thereby to shorten the distance between said edge engaging means, and means for retaining 25 the coils of said film in spaced relation.
3. A device of the class described, comprising, in combination, a two-part hub adapted to receive a strip of film in spiral formation, one part being movable toward and away 30 from the other, means carried by said hub for locally engaging the edges of the film, means for clamping said hub parts together thereby to shorten the distance between said edge engaging means, means for limiting

said clamping action, and means carried by 35 said edge engaging means for retaining the coils of said film in spaced relation.

4. A device of the class described, comprising a pair of hub members one adapted to slide toward and away from the other in the 40 direction of the length of the hub, a plurality of radially extending spokes carried by each of said hub members, and means for clamping the hub members in abutting relation.

5. A device of the class described, comprising a pair of hub members one adapted to slide toward and away from the other in the direction of the length of the hub, a plurality of radially extending spokes carried 45 by each of said hub members, a flexible casing enclosing each of said spokes, and means for clamping the hub members in abutting relation.

6. A device of the class described, comprising a pair of hub members one adapted to slide toward and away from the other in the direction of the length of the hub, a plurality of radially extending spokes carried by each 50 of said hub members, a rim for each hub member attached to the outer ends of its spokes, and means for clamping the hub members in abutting relation, said rims being of such width that the rims and hub members are respectively brought into abutting 55 relation simultaneously.

In testimony whereof I have signed my name to this specification.

LÁSZLÓ CZAKÓ.
